UNITED STATES PATENT OFFICE.

DAVID YOAKAM, OF LACONA, IOWA.

RAIL-JOINT.

1,079,820.

Specification of Letters Patent. Patented Nov. 25, 1913.

Application filed June 19, 1912. Serial No. 704,659.

To all whom it may concern:

Be it known that I, DAVID YOAKAM, a citizen of the United States, residing at Lacona, in the county of Warren and State 5 of Iowa, have invented new and useful Improvements in Rail-Joints, of which the following is a specification.

The invention relates to rail joints, and the primary object of the same is to provide 10 a joint of an overlapped character which will retain the full strength of each rail and materially reinforce the joint of the rail ends or extremities, and, furthermore, provide a greater width of bearing on the ties 15 at the joint as compared to ordinary rail joint structures without the aid of chairs to effect a uniformity in bearing as regards elasticity to the track, which is an important item in the durability of a railroad track.

20 A further object of the invention is to provide means for associating the ends of rails in such manner as to produce an angular joint where the rail extremities meet and also to produce a tread surface 25 of greater width to prevent the wheels jumping or jolting when the rails contract and leave an open joint and insure a more uniform and even surface to the track, and also to provide a greater bearing area on the 30 ties at the joints with less liability to spreading or slipping action by lateral pressure of the wheels exerted on the rails.

A still further object of the invention is to 35 provide means for preserving the continuity of the track at the joints without impairing its strength and also to obviate any tendency to loose movement of the rail joint in a vertical direction as well as in opposite lateral directions and thereby prevent derailments 40 and other accidents. The improved joint also reduces the labor and cost incident to track repair as now commonly incurred at the joints and which arises from the fact that the ordinary rail joints are liable to 45 spring or work loose and shear the bolts, the latter disadvantages being fully overcome by the improved joint.

With these and other objects and advantages in view the invention consists in the 50 construction and arrangement of the several parts which will be more fully hereinafter described and claimed.

In the drawings: Figure 1 is a perspective 55 view of a rail joint embodying the features of the invention. Fig. 2 is a similar view of the parts of the joint or the rail sections

in separated relation. Fig. 3 is a transverse vertical section on the line 3—3, Fig. 5. Fig. 4 is a transverse vertical section on the line 4—4, Fig. 5. Fig. 5 is a top plan view 60 of the improved joint.

The numeral 5 designates a rail section of ordinary form, and 6 a rail section having an offset 7 providing a longitudinal seat 8 to flushly receive the extremity or end of the 65 rail section 5, as clearly shown by Figs. 1 and 5. The offset 7 in the main is of the same proportions and dimensions as the rail section 6 of which it forms a part, that is, it has a head 9 with a tread surface 10 and a base flange 11 connected to the head by a web 12, the head 9 and flange 11 being approximately similar in dimensions to the head and flange at one side of the center of the web of the rail section 6. The web 12 70 of the offset is materially thicker than the web of the rail sections 5 and 6 and continues into an inwardly projecting longitudinally extending boss or enlargement 13 which provides a combined reinforcing filling and supporting means in a manner 75 which will be presently explained. The upper edge of the boss or enlargement 13 is downwardly inclined to form a supporting shoulder 14 adapted to fit under the adjacent portion of the head of the rail section 5 which is brought into engagement with the offset 7, and the lower edge of said boss or 80 enlargement is also downwardly and outwardly inclined to provide a base shoulder 90 15 to fit over the outer portion of the flange of the rail section 5 which is associated with the offset, the shoulder 15 being long enough to permit the boss or enlargement 13 to snugly fit in against the web of the extremity of the rail section 5 between the inner portion of the head and of the base flange of the said latter section. It will be seen that the extremity of the rail section 5 which 95 engages the offset is supported against depressing and rising movements by the boss or enlargement 13, and the end 16 of the rail section 5 abuts against the corresponding end 17 of the rail section 6, the said end 17 being cleared for this abutting engagement 100 with relation to the end 16 of the rail section 5 by projecting the offset fully clear of the web and head as well as the base flange of the section 6, as shown by Fig. 2, and when the tread surface 10 of the offset 7 105 and the tread surface of the adjacent extremity of the rail section 5 are associated,

a tread surface having double the width of an ordinary rail web is produced, as clearly shown by Figs. 1 and 5, and the base support in cross-sectional extent is materially 5 greater than in ordinary rail joint structures by reason of the flange 11 of the offset added to the ordinary flange width of the rail sections 5 and 6.

The increased width of the improved 10 joint as provided by the association of the offset 7 and the extremity of the rail section 5 gives an extended bearing for the joint of the rail sections on the support or ties 18, as shown by Fig. 1, and the offset and 15 the extremity of the rail section 5 have fish plates 19 applied thereto, as clearly shown by Fig. 3, and the whole secured by bolts 20 passed through the offset and rail extremity and the said fish plates. It will 20 also be seen that the offset is secured to the ties by spikes engaging the flange 11, and similarly the inner flange of the extremity of the rail section 5 will be secured by spikes, as clearly shown by Figs. 3 and 5. 25 After the parts of the joint have been practically associated as shown by Figs. 1 and 5, it will be impossible for either the offset 7 or the extremity of the rail section 5 to spring up or be depressed, and a very strong 30 and increased resistance is provided against lateral displacement of the rail sections at the joint. Furthermore, the wheels of the rolling stock in traveling over the parts of the joint by reason of the rigidity of the latter and the resistance to springing movement will have an easy action or be free from jolt and jar and less wear will ensue on the wheels with a material saving in the durability and practical service of the 35 40 wheels and the comfort and convenience of the passengers as well as reduced vibration on the parts of the cars disposed on the trucks moving over the joints.

The additional cost of forming the offset 45 in the manner hereinbefore described will be more than compensated for by the durability and longer wearing period of the rails at their jointed ends and especially in view of the fact that less repair will be required. 50 A further advantage of the improved joint is that the rail extremities by reason of the

offset may be readily and accurately associated when the rails are laid, the offset being longitudinally straight or in the main parallel with the rail section of which it 55 forms a part, and hence when the extremity of the associated rail is disposed against the offset as shown by Fig. 1, a straight disposition of the several rail sections will be assured. The improved joint embodying the 60 offset also dispenses with the necessity of using rail chairs or supporting plates under the rail flanges with material advantage in a saving in the cost of railroad construction or economy in railroad maintenance. 65

What is claimed is:

In a rail joint, the combination of a rail section having an angular offset at one end of substantially the same configuration as the body of the said rail section and extending in the main longitudinally straight in a plane parallel to the section to provide a straight transverse abutting shoulder and a seat, the transverse extent of the shoulder and seat being just equal to the cross-sectional extent of an ordinary rail extremity, the offset between the upper and lower surfaces thereof having a longitudinal boss which is in addition to the thickness of the offset and has a vertical extent less than the 70 maximum vertical extent of the offset and a thickness less than the transverse extent of the recess formed by the offset, and a second rail section of normal contour and proportions having its extremity fitted in the said 75 recess flush with the portion of the rail extremity carrying the offset with the said boss snugly fitting in the side of the said second rail section between the head and the base flange of the latter, the one side of the 80 head of the second rail section being supported on the upper edge of the boss below the top surface of the offset, and means extending through the two rail sections for securing them. 85

In testimony whereof I have hereunto set my hand in presence of two subscribing witnesses.

DAVID YOAKAM.
